(57) **CLAIM**

The ornamental design for a watch hand, as shown and described.

DESCRIPTION

FIG. 1 is a top perspective view of a watch hand showing my new design;

FIG. 2 is a bottom perspective view thereof;

FIG. 3 is a side view thereof;

FIG. 4 is a front view thereof;

FIG. 5 is a rear view thereof (looking at the butt of the handle);

FIG. 6 is a top view thereof;

FIG. 7 is a bottom view thereof;

FIG. 8 is an environmental perspective view thereof; and,

FIG. 9 is a second environmental view thereof.

The portions of the figures shown in broken lines form no part of the claimed design.
